UNITED STATES PATENT OFFICE.

HOWARD K. KING, OF PHILADELPHIA, PENNSYLVANIA, ASSIGNOR TO
CHAMBERS BROTHERS COMPANY, A CORPORATION OF PENNSYLVANIA.

FOLDING-MACHINE.

No. 801,994.

Specification of Letters Patent.

Patented Oct. 17, 1905.

Application filed February 4, 1905. Serial No. 244,074.

To all whom it may concern:

Be it known that I, HOWARD K. KING, a citizen of the United States, residing at Philadelphia, in the county of Philadelphia and State 5 of Pennsylvania, have invented a new and useful Folding-Machine, of which the following is a specification.

My invention relates to improvements in folding-machines, and comprises improved 10 means for the arrangement of the carrying-tapes so that pairs of said tapes may travel together one above the other in the same direction for conveying superimposed signatures.

My invention is especially useful in connection 15 with what are commonly known as "double-sixteen" machines.

My invention comprises improved means for returning two or more of said tapes so as not to interfere with the operation of the machine.

Referring to the drawings, Figure 1 is a plan view of an ordinary folding-machine containing my improved means. Fig. 2 is a vertical section on line 2 2 of Fig. 1. Fig. 3 is 25 a vertical section on line 3 3 of Fig. 1. Fig. 4 is a vertical section on lines 4 4 of Fig. 3. Fig. 5 is a plan view of the mechanism shown in Fig. 4. Fig. 6 is a vertical section on line 6 6 of Fig. 5. Fig. 7 is a vertical section on 30 line 7 7 of Fig. 5.

Similar numerals refer to similar parts throughout the several views.

The folding-machine shown in plan view in Fig. 1 is of the same general type as that 35 shown in patents to me, Nos. 667,021 and 667,022, dated January 29, 1901, with the exception of the details herein described. In Fig. 1 the sheet is shown as having passed through the folding-rollers 1 and 2 and at the 40 same time having been cut in two parts or signatures 3 and 4 by the cutter 5, as shown in Fig. 3, operating in the groove 6 of roller 1. The abutting ends of sheets 3 and 4 are shown separated by the bar 7. These signatures are 45 now carried upon the tapes 8 in the direction of the arrow until their front edges encounter the stops 9. Signature 3 is struck through rollers 10 and 11, while signature 4 is struck through rollers 12 and 13. The signature 3 50 is delivered by rollers 10 and 11 to tapes 14, traveling in the direction of the arrow, (see Fig. 2,) while signature 4 is carried through rollers 12 and 13 and on tapes 15. The operations of the machine are so timed that a sig-

nature from rollers 10 and 11 will be delivered upon tapes 14 over a signature carried on tapes 15, delivered from rollers 12 and 13, so that said two signatures 3 and 4 will register when brought to rest against stop 45 over rollers 16 and 17, so that one signature will be 55 folded or inset within the other. One of the objects of my invention is to provide means for supporting the tapes 14 and 15 so that they will travel in the same direction close together and one above the other and so as to prevent 60 any interference of the returning tapes with said signatures. This co-operation of tapes 14 and 15 secures a more complete control of the travel of the signatures and obviates the necessity for the use of separating-bars to prevent 65 displacement of the signatures. At the same time the return of said tapes is secured in such a way as not to obstruct or interfere with the operation of the machine. As will be seen in Fig. 2, tapes 15 return about rollers 18, 26, 19, and 13, and tapes 25 return about rollers 18, 26, 27, and 28 in the usual way. Tapes 14, however, are made to return about rollers 20, 21, 22, 23, and 12 between 70 the severed sections or signatures 3 and 4 after 75 the sheet has received its first fold.

The returning of the tapes 14 over the top of the machine is made possible by the following mechanism: Bar 7 is suitably supported to the stationary parts of the machine at 80 one end by the bracket 29, secured by the set-screw 42, and at the other end by the bracket 30, secured by the set-screw 43. In this bar 7 are provided the apertures 31, through which the tapes 14 pass. To this bar 7 are secured 85 the brackets 32 and 33, upon which are mounted the rollers 22 and 23, which serve to guide the tapes 14 through the apertures 31. At the end of the bar 7, which encounters the advancing sheets, are provided the deflecting 90 members or extensions 34 and 35, 34 being integral with the supporting-bracket 30 and 35 being secured to the bar by the rivets or bolts 36 or by any other suitable means. The end of bar 7 is also notched, as at 37, (see Figs. 5 and 7,) and is also provided with the guide channels or grooves 38 and 39 in said notch. The supporting guide-rod 40 is also provided 95 in connection with bar 7, being held in position by the bracket 41, secured to said bar 7. 100

By the above-described mechanism it will be seen that when the sheet receives its first fold and is delivered through the rollers 1 and 105

2, cut into two separate signatures, the deflecting member 35 will encounter the under edge of signature 4 (see Fig. 3) and guide or deflect said edge along the top of deflector 35 to the top surface of bar 7, while the deflector 34 will encounter the upper side of the edge of signature 3 (see Fig. 6) and deflect it downwardly under bar 7. The rod 40 will serve to support the under side of said signature 3 as it travels under bar 7. The guiding grooves or channels 38 and 39 will insure the proper separation of said two signatures, so that they will not catch or stick, but will slide smoothly along the deflectors and be properly directed, as above described. It is obvious that as one signature moves along the top of bar 7 while the other moves beneath it and upon the other side thereof a space is maintained cleared for the travel of the tapes 14 through apertures 31 without any danger of interfering with said sheets.

What I claim is—

1. In combination with a folding-machine, means for deflecting the abutting edges of traveling sheets one above and the other below the plane of said traveling sheets and tape-supporting rollers so positioned as to guide the tape through the space between said deflected edges.
2. In combination with a folding-machine, a horizontal bar having deflecting members for encountering the abutting edges of traveling sheets, and rollers supported by said bar for guiding the tapes between said deflected edges.
3. In combination with a folding-machine, an apertured bar and deflecting means connected therewith for separating the abutting edges of traveling sheets and tape-rollers so positioned as to guide the return-tapes through the apertures of said bar.
4. In combination with a folding-machine, an apertured bar and means connected therewith for deflecting the abutting edges of traveling sheets so that one shall travel above the bar and the other beneath it, and tape-rollers so positioned as to guide the tapes through the apertures.
5. In combination with a folding-machine, an adjustable bar and means connected therewith for deflecting the abutting edges of traveling sheets so that one shall travel above the bar and the other beneath it, and tape-rollers so positioned as to guide the tapes through the apertures.
6. In combination with a folding-machine, an apertured bar and means connected therewith for deflecting the abutting edges of traveling sheets so that one shall travel above the bar and the other beneath it comprising deflectors for encountering said sheets and divergent guide-channels coöperating therewith, and tape-rollers so positioned as to guide the tapes through the apertures.
7. In combination with a folding-machine, an adjustably-mounted bar, having a notched

end and divergent guide-channels therein and coöperating deflecting members for encountering the abutting edges of traveling sheets to cause the separation thereof so that one edge shall travel above the bar and the other beneath it, and means for guiding the tapes through the apertures of the bar.

8. In combination with a folding-machine, an adjustably-mounted bar, having a notched end and divergent guide-channels therein and coöperating deflecting members for encountering the abutting edges of traveling sheets to cause the separation thereof so that one edge shall travel above the bar and the other beneath it, means for guiding the tapes through the apertures of the bar, and a guide-rod beneath the bar for supporting the edge of one sheet.

9. In combination with a folding-machine, means for supporting overlying tapes traveling in the same direction, comprising means for returning one set of tapes from over one, to beneath the other, of a pair of parallel sheets or signatures traveling in the same plane.

10. In combination with a folding-machine, means for supporting overlying tapes traveling in the same direction each tape adapted to carry a separate signature, comprising means for guiding one set of tapes between the abutting edges of a pair of signatures traveling in the same plane from over one to beneath the other of said signatures.

11. In combination with a folding-machine, means for supporting overlying tapes, traveling in the same direction, so that the returning tapes shall not interfere, said means comprising a horizontal bar with oppositely-disposed deflecting guides and diverging guide-channels starting from a common point or edge, one having an upwardly slant and the other a downwardly slant.

12. In combination with a folding-machine, means for supporting overlying tapes traveling in the same direction, so that the returning tapes shall not interfere, comprising means for deflecting the abutting edges of a pair of traveling signatures one above and the other below the plane of said signatures, and tape-supporting rollers so positioned as to guide the tape through the space left thereby.

13. In combination with a folding-machine provided with traveling tapes for carrying the signatures to the required positions, means for supporting pairs of said tapes so that the tapes of each pair shall travel in the same direction, close together and one above the other, to coöperate in carrying superimposed signatures said supporting means comprising rollers so positioned as to guide one set of tapes between the abutting edges of a pair of signatures over one and under the other of said pair of signatures, and then back under the first signature.

14. In combination with a folding-machine

provided with traveling tapes for carrying the signatures to the required positions, means for supporting pairs of said tapes so that the tapes of each pair shall travel in the same direction, close together and one above the other, to coöperate in controlling the travel of superimposed signatures comprising means for guiding one set of tapes between the abutting edges of a pair of sheets or signatures traveling in the same plane, from over one of said signatures to beneath the other of said signatures, and then back beneath the first signature.

15. In combination with a folding-machine provided with traveling tapes for carrying the signatures to the required positions, means for supporting pairs of said tapes so that the tapes of each pair shall travel in the same direction, close together and one above the other, to coöperate in carrying superimposed signatures, said supporting means adapted to guide one set of tapes between the abutting edges of a pair of sheets or signatures traveling in the same plane, from over one sheet or 25 signature to a folding-roller beneath the other

sheet or signature, and then back under a pair of folding-rollers beneath the first sheet or signature.

16. In combination with a folding-machine provided with traveling tapes for carrying the signatures to the required positions, means for supporting pairs of said tapes so that the tapes of each pair shall travel in the same direction, close together and one above the other, to coöperate in carrying superimposed 30 signatures, said tape-supporting means adapted to guide a set of tapes between the abutting edges of a pair of sheets or signatures traveling in the same plane, over one sheet or signature and beneath the other sheet or 35 signature to and about one of a pair of folding-rollers located beneath said second sheet or signature and then back beneath a pair of folding-rollers located beneath the first sheet or signature.

HOWARD K. KING.
